UNITED STATES PATENT OFFICE

VICTOR ROSENHAGEN, OF BELLEVUE, KENTUCKY, ASSIGNOR TO THE BREESE BROTHERS COMPANY, OF CINCINNATI, OHIO, A CORPORATION OF OHIO

VACUUM CONDENSATION SYSTEM

Application filed April 4, 1932. Serial No. 603,007.

This invention relates to a vacuum condensation system especially applicable in steam heating installations.

An object of the invention is to provide such a system operable under low steam pressure.

Another object is to provide novel valve means controlling operations of the vacuum condensation apparatus.

10 Another object is to eliminate the waste and inefficiency heretofore present in older systems wherein it has been necessary to maintain a high steam pressure although the heating requirements at a given time might have 15 been relatively low.

These and other objects are attained by the means described herein and illustrated in the accompanying drawing, in which:

Fig. 1 is an elevational, partly schematic 20 view of an installation of the invention, with parts broken away.

Fig. 2 is a vertical cross sectional view of the thermostatic control means utilized in the present invention.

25 Fig. 3 is a vertical cross sectional view of a portion of the vacuum creating means utilized herein.

Fig. 4 is an elevational view, partly in cross 30 section and partly broken away, of the automatic valve means for separately introducing liquid condensation and return air or vapor into the return depository.

Fig. 5 is a cross sectional view taken on line 5—5 of Fig. 1.

35 With reference to the drawing:

A boiler or steam source 10 is provided, from which steam under pressure is supplied through a suitable line 11 to the radiators of a heating system, one of the radiators 40 being indicated at 12.

Vacuum creating means are provided for drawing air and liquid condensation from the system. These means comprise a circulation tank 13 and a vacuum tank or condensation 45 chamber 14.

The circulation tank 13 is maintained substantially half full of water as indicated at 15 for supplying a centrifugal pump 16 positioned laterally of and in communication with the interior of tank 13. Pump 16 may be driven by a suitable motor 17. The pump communicates by a pipe 18 with the interior of circulation tank 13 at the top thereof. Between the lower end of pipe 18 55 and motor 17 is interposed vacuum creating

means 19. This means comprises an ejector or nozzle 20 (Fig. 3) projecting into a vacuum chamber 21 and directing a forced stream of water into a restricted receiver 22, spaced from the end of the ejector 20. This action sets up a vacuum in the vacuum line 23 (Fig. 1), in which line a check valve 230 may be provided. Said line extends into the condensation chamber 14, through the top thereof, and terminates in an open end 24, disposed substantially half way down said chamber. A volume of water in chamber 14 has its lowest level 25 disposed immediately beneath the open end 24 of line 23, said water serving as a seal through which all air, drawn from the heating system through the intake pipe 26, must pass. In this way, the steam or vapor from the heating system becomes condensed, since the intake port 260 is disposed at the bottom of chamber 14.

The return pipe 27 of the heating system communicates at its inner end with the enclosing chamber 28 of a float valve 29. When sufficient liquid condensation has been taken into chamber 28 to float the valve 29, the latter rises from its seat 30 (Fig. 4) and admits the condensation into the pipe 31 which

communicates as at 32 with intake pipe 26. The intake pipe 26 is of such length as to effect sufficient cooling of the condensation for precluding return thereof to a steam state within the condensation chamber 14. When no liquid condensation is present in valve 30, the float 29 drops to position

upon its seat 30. At this time the air passing through the heating system is drawn into the lower end of a tube 35. Before entering said tube, the induced air passes through a casting 37 (Fig. 2) surrounding a thermostatic valve 38 which prevents steam above atmospheric pressure from entering the chamber 14

and which closes when the temperature of the entering air exceeds 212 degrees but remains partly open at a temperature of about 200 degrees.

As heretofore explained, the liquid condensation in the heating system is drawn into the chamber 14. When the volume of water therein is so increased that the level rises above the pipe end 24, water is drawn off until the level 25 is restored, said drawn water

passing through vacuum line 23 to enter the vacuum chamber 21 where it joins with the water being forced through pipe 18 into the circulation tank 13.

100 As heretofore explained, the liquid condensation in the heating system is drawn into the chamber 14. When the volume of water therein is so increased that the level rises above the pipe end 24, water is drawn off until the level 25 is restored, said drawn water

passing through vacuum line 23 to enter the vacuum chamber 21 where it joins with the water being forced through pipe 18 into the circulation tank 13.

A float valve 39 (Figs. 1 and 5) is provided in tank 13 to control discharge of water above a selected level from the tank through an overflow line 40 into the boiler 10. Said 5 valve comprises a float 41 slidable in a casing 42 and having at its top a rod 43 vertically movable in a guide 44 and having a stop 45 secured to its upper end within the guide 44. Until the upper end 46 of float 41 has 10 been moved upwardly by an increasing volume of water into contact with the end of guide 44, the air carried into tank 13 is allowed to escape through vents 47 provided in the exterior portion 48 of the valve 39. 15 But when end 46 of the float 41 contacts the bottom end of guide 44, the latter is carried up until a valve member 49 secured at its top end becomes positioned in a valve seat 50, whereby access to the vents 47 is closed off. 20 Thereafter the increasing air pressure against the water level causes some of the water to flow out through line 40 to boiler 10 against a steam pressure not exceeding 15 pounds. The flow of water continues until the water 25 level in tank 13 is lowered and the air pressure decreases, permitting the reopening of the valve 49. A check valve is provided in line 40 as at 51. The association of float 41 with the valve member constitutes a lost 30 motion connection. In Fig. 5, the float 41 is shown as descending after having been moved upwardly by the water, there still being sufficient air pressure within the tank, in the circumstances illustrated in Fig. 5, to 35 hold the valve member 49 closed. By this means an effective evacuation of excess liquid condensation from the tank is attained.

It will be understood that the vacuum system described is adapted to effect the movement of steam under low pressure through a heating installation. It will be further understood that, under the ideal condition or optimum efficiency of a heating system, the steam in the system and the atmospheric condition exterior thereto are counterbalanced so that the steam would be in a substantially static state. However, in actual practice, there are frequent variations from this ideal condition whereby a slightly lowered atmospheric temperature results in a limited amount of liquid condensation in the steam lines. It will be understood that a static vacuum is created above the water seal in chamber 14. This static vacuum is utilized 40 within a selected range, for drawing from the heating system the limited condensation such as described without necessitating the re-starting of the vacuum creating means 19 and associated parts. The variation of the 45 vacuum in chamber 14 may be recorded upon a suitable indicator 52 which may be adjusted as desired and which has electrical connection with a switch 53 adapted to start the motor 17 when said indicator 52 registers 50 below a selected point. For example, the mo-

tor may be cut out when a vacuum of 10 inches is recorded and started again when a vacuum of 6 inches is registered. The starting of the motor sets up the vacuum through the heating system which continues until the indicator 52 again reaches its selected high point at which time the switch 53 is automatically moved to the "off" position. 70

What is claimed is:

1. Vacuum condensation means for steam 75 heat systems and comprising a circulation tank communicating with the steam boiler of said system, a condensation chamber communicating with said tank and the return pipe of the system, a water seal in the condensation chamber, means interposed in the communicating medium between said tank and chamber for creating a vacuum adapted to draw air and liquid condensation from the system through said water seal into said chamber and tank successively, said means being adapted to create a static vacuum above the water seal in the condensation chamber, means 80 successively stopping and starting operation of the vacuum creating means upon arrival of said static vacuum at a selected high and low sub-atmospheric pressure, respectively, means associated with the condensation chamber to preclude entry therein of less than a given volume of liquid condensation and of 85 induced air of greater than a given temperature, and means operative upon the exceeding of a given volume of water in the circulation tank for effecting outflow of the excess water from said tank to the steam boiler. 90

2. In an apparatus of the class described the combination with a heating system including a boiler and return pipe, of a vacuum condensation chamber, a circulation tank, a vacuum pump consisting of means to pump 105 water from the bottom of the tank and to discharge it into the upper portion of said tank, a pipe having an open end associated with said pump and an open end disposed in said vacuum condensation chamber above the bottom thereof, whereby said condensation chamber is incompletely exhausted of water at all times, a thermostatic valve and casing connected to said return pipe of the heating system, a float casing communicating at its top 110 with said return pipe and at its bottom with the bottom of the condensation chamber, a valve controlled by the said float, a tube connected to the thermostatic casing above the thermostatic valve and to the condensation chamber near the bottom thereof, an air exhaust valve in the circulation tank, float means in said tank having a lost motion connection with said air exhaust valve, power means to drive the pump, and a vacuum controlled switch and electrical circuit operating to energize the power means to the pump when the pressure in the condensation chamber exceeds a predetermined amount and to deenergize the power means when the pres- 120 125

sure is reduced to a different predetermined amount.

3. In a device of the class described the combination of a vacuum condensation chamber having a water seal, power actuated means for exhausting air and water from said chamber, means for connection with a return pipe of a low pressure heating system whereby condensation is accumulated for intermittent discharge into the condensation chamber below the water seal, other means including a thermostatic valve for normally exhausting air and low temperature vapor from the return pipe to said condensation chamber below said water seal and vacuum controlled switch and circuit means energizing and de-energizing the power means at predetermined degrees of low and high evacuation of said vacuum condensation chamber whereby air may be withdrawn from the system after the power means is deenergized.

4. Vacuum condensation means for low pressure steam heat systems and comprising a condensation chamber having a water seal therein, vacuum creating means for drawing air and liquid condensation from the system through said water seal into said chamber, said means being adapted to create a static vacuum above the water seal in said chamber, means successively stopping and starting operation of said vacuum creating means upon arrival of said static vacuum at a selected high and low sub-atmospheric pressure, respectively, means associated with the condensation chamber to preclude entry therein of less than a given volume of liquid condensation and of induced air of greater than a given temperature, means for discharging from the condensation chamber the excess of water above the volume constituting the water seal, and means cooling the liquid condensation before entry thereof into the condensation chamber.

5. Vacuum condensation means for a steam heat system and comprising a tank, an overflow pipe therein, means for drawing air and liquid condensation from the system into the tank, and valve means associated with the tank and comprising an air vent normally permitting escape of indrawn air, a valve controlling communication of the vent with the tank, and a float having a lost motion connection with said valve and adapted, upon rise of the liquid condensation in the tank above a selected level, to close the valve whereby the pressure of indrawn air effects discharge from the tank of the excess liquid condensation through the overflow pipe, said lost motion connection permitting continued closure of the valve by air pressure for a limited period after the float has begun to de-

scend whereby an effective evacuation of excess liquid condensation is attained.

6. The combination with a steam heat system or the like comprising a vacuum condensation chamber, of means for effecting intermittent discharge of liquid condensation from the system into said chamber and comprising a valve chamber communicating with the return pipe of the heat system and with said condensation chamber, said valve chamber having a valve seat in the bottom thereof and a float valve therein adapted normally to remain positioned in said seat and to be displaced from said seat for permitting access into the condensation chamber only upon accumulation in the valve chamber of a given volume of liquid condensation.

7. The combination in a steam heat system or the like, of a vacuum condensation chamber having an inlet port adjacent the bottom thereof and a water seal in the chamber for said port, an inlet pipe communicating with said chamber through said port and extending above the level of said water seal, a return pipe in the system, a float valve mechanism communicating with the return pipe and with the lower outer portion of said inlet pipe and precluding entry into the inlet pipe of less than a given accumulated volume of liquid condensation, means associated with the inlet pipe for cooling condensation therein to preclude return thereof to a steam condition within the condensation chamber, and a thermostatic valve communicating with said return pipe and having tubular connection with the upper portion of the inlet pipe, said thermostatic valve being operative when the float valve is closed for admitting air of less than a predetermined temperature into the inlet pipe and for excluding therefrom air of greater than a predetermined temperature.

8. The combination in a steam heat system or the like of a vacuum condensation chamber having an inlet port adjacent the bottom thereof and a water seal for the port in the chamber, an inlet pipe communicating with said port, a return pipe in the system, a float valve mechanism communicating with the return and inlet pipes and precluding entry into the inlet pipe of less than a substantial accumulation of condensation, said inlet pipe being of sufficient length for cooling the condensation before entry thereof into said chamber, and a thermostatic valve and casting communicating with the return and inlet pipes and adapted to admit air of less than a predetermined temperature into the inlet pipe and to exclude therefrom air of greater than a predetermined temperature.
